UNITED STATES PATENT OFFICE.

CURTIS M. BALLINGER, OF LUBBOCK, TEXAS.

DENTAL APPLIANCE.

1,080,878.

Specification of Letters Patent.

Patented Dec. 9, 1913.

Application filed March 25, 1913. Serial No. 756,783.

To all whom it may concern:

Be it known that I, CURTIS M. BALLINGER, a citizen of the United States, residing at Lubbock, in the county of Lubbock and State 5 of Texas, have invented a new and useful Dental Appliance, of which the following is a specification.

This invention relates to a dental appliance and is more particularly an attachment 10 for dental engines whereby the dental bur of carborundum or the like can be kept cool while in use.

A further object is to provide an attachment of this character the operation of 15 which is constantly under the ready control of the operator who can regulate the flow of the cooling medium without changing the position of his hand upon the bur carrying tool.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—Figure 1 is an elevation of the attachment in position, the tool holder being shown in position with a bur 35 connected thereto. Fig. 2 is an enlarged longitudinal section through the nozzle of the attachment. Fig. 3 is an enlarged section on line A—B Fig. 2. Fig. 4 is an enlarged section on line C—D Fig. 2.

40 Referring to the figures by characters of reference 1 designates the ordinary tool holder of a dental engine and a bur has been indicated at 2.

The attachment constituting the present 45 invention includes a combined nozzle and valve of novel form adapted to be attached to the holder 1 by means of bands 3, clips or the like. This attachment has a cylindrical casing 4 formed with a longitudinal pas-

50 sage 5 along the outer side thereof and which communicates with the interior of the casing through a port 6. Passage 5 is extended beyond the closed end of the casing to form a tapered nozzle 7 which, when the attachment is in position on the holder 1, is sup-

ported close to the back face of the bur 2. A tubular valve 8 is fitted snugly within the casing 4 and is adapted to rotate therein, this valve being provided with a port 9 adapted to move into and out of register with the port 6 when the valve is rotated within the casing or when the casing is rotated on the valve. The valve 8 is extended beyond one end of the casing and secured to this projecting end is one end of a flexible tube 10 which extends to a reservoir 11. This reservoir is adapted to be supported at a point above the casing 4 so that water will be free to gravitate from the reservoir or tank into the valve 8. Casing 4 is provided at its open end with an exteriorly screw threaded head 12 counter-bored as at 13 to form a seat to receive a packing ring 14. An annular flange 15 is formed on the valve 8 and bears against the packing ring 75 14, said flange being held against the packing by a nut 16 which is counter-bored as shown so as to receive the head 12 and screw thereon. This nut is adapted to bear against the flange 15 as shown in Fig. 2 and when 80 the parts have been tightened, it will be apparent that the escape of water therebetween will be prevented without, however, interfering with the rotation of the valve 8 within the casing 4. A finger piece 17 extends from the valve 8 back of the head 12 85 and constitutes means whereby the valve can be rotated so as to shift its port 9 into or out of register with the port 6.

When the device is in use, it extends along 90 the holder 1 and the flexible tube 10 serves to hold the valve 8 normally in closed position with the port 9 out of register with the port 6. Nozzle 7 extends up close to the bur 2 and, whenever it is desired to direct a jet of water against the bur, the operator presses downwardly on the finger piece 14 so as thus to cause the valve 8 to rotate within the casing and bring the port 9 into register with port 6. Water will therefore 100 flow downwardly from the tank or reservoir 11 into the passage 5 and thence into the nozzle 7 from which it will be directed against the bur, as shown in Fig. 1.

Attention is called to the fact that the 105 device is very small and compact in construction and will not, therefore interfere with the insertion of the bur and its holder into the mouth of the patient and the proper manipulation of the bur upon the tooth. 110

It is not necessary for the operator to change the position of his hand upon the holder in order to actuate the finger piece 14.

What is claimed is:—

- 5 An attachment for the tool holder of a dental engine, including an elongated casing closed at one end, a nozzle extending beyond said closed end of the casing and along the wall of the casing, said nozzle opening 10 into the casing, a tubular valve mounted for rotation in the casing and having an annular enlargement abutting against the open end of the casing, there being a port within the valve adapted to establish communication 15 between the interior of the valve and the nozzle, means engaging the casing and

the annular enlargement for holding the valve against longitudinal displacement in the casing, a flexible tube connected to one end portion of the valve for directing fluid 20 into the valve, and a finger piece extending outwardly from the valve and constituting means for rotating the valve within the casing.

In testimony that I claim the foregoing 25 as my own, I have hereto affixed my signature in the presence of two witnesses.

CURTIS M. BALLINGER.
